ATTORNEY

UNITED STATES PATENT OFFICE.

MAYNOR D. BROCK, OF KANSAS CITY, MISSOURI.

TOY VEHICLE.

1,369,777.

Specification of Letters Patent.

Patented Mar. 1, 1921.

Application filed July 30, 1918. Serial No. 247,354.

To all whom it may concern:

Be it known that I, MAYNOR D. BROCK, a citizen of the United States, residing at Kansas City, in the county of Jackson and State of Missouri, have invented certain new and useful Improvements in Toy Vehicles; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 This invention relates to vehicles adapted to be operated by juveniles, and one of the objects of the invention is to provide a vehicle which the child may readily manipulate, which is adapted to be propelled by pedaling against the surface over which the vehicle travels, which is adapted to be used as a coaster, and which is adapted to be drawn if desired, by a second party through the medium of a cord or rope, which will direct the car without the aid of the occupant of the car if so desired.

20 Another object of the invention is to furnish a seat provided with a support confined within narrow limits so that the feet and lower part of the legs of the operator may assume substantially a vertical position and not necessarily a sidewise position and so that the knees of the operator may remain near together instead of being forced to be

25 spread apart as is common with some of the devices in use which have an arrangement in which the width of the support parallel with the surface of the earth instead of perpendicular to it as in this device, one of the

30 aims being to prevent friction on the private parts of the young operator.

35 Another aim of this invention is to have the back wheels of the vehicle well back so they will not interfere with the feet of the operator and so the skirt of the child will not touch them readily if at all.

40 It is also the purpose of the invention to hinge the body portion in between its ends so that it may be guided by the occupant or

45 guided by means of a cord from the front with equal facility.

50 It is also the purpose of this invention to provide a device of the class described which may be rendered vertically adjustable.

55 Other objects and advantages of the invention will appear hereinafter, it being

understood that changes in form, proportion, and minor details of construction may be resorted to without departing from the spirit of the invention or sacrificing any of its advantages.

In the drawings—

Figure I is a perspective view of a vehicle constructed in accordance with my invention.

Fig. II is a side elevational view of the same.

Fig. III is a sectional view through the line III—III of Fig. II.

Fig. IV is a sectional view through the forward hinge joint, and

Fig. V is a perspective view of a modified form of the device.

Referring now to the drawings by numerals of reference:

1 designates a body portion or seat supporting beam which consists of a block or beam having a hinged forward steering head 2, the hinge being best shown in Fig. IV as being mortised in the parts 1 and 2 as shown at 3 and 4. The leaves 5 and 6 of the hinges are fastened in place by fastening devices 7 and 8 and the adjacent edges of the parts 1 and 2 are rounded, chamfered or beveled to permit the steering head to be

75 swung on a relatively wide arc.

Upon the rear portion of part 1 is a transverse back or support having a plurality of openings 10 in which the axle 11 is adjustably mounted, said axles supporting the wheels 12 and 13. Intermediate the ends of the member 1 is a cutout portion or depression 14 adjacent to the seat 15 whereby the operator's legs may have freedom, whereby a skirt may be allowed to drop and assume 95 its normal position with respect to the operator, the thin narrow member 1 permitting the legs to remain closed together at all times and not causing friction on the private parts of the operator during pedaling.

100 On the steering head is a steering handle or bar 16 which may be grasped by the operator in a convenient manner to run the head either to the right or the left. I have provided means whereby the seat supporting beam may be adjusted vertically and this is accomplished by providing adjusting openings 17 and 18 in the steering head which in conjunction with the openings 10 permit the seat supporting beam 1 to be raised and 110 lowered. When it is desired to adjust the beam 1 the hinge fastenings 7 and the axle

11 may be removed and after raising the hinge leaf 5 and with it the beam 1 and back 9 the fastenings 7 and the axle may be placed in the next highest hole or openings or for extreme adjustment the axle 19 for the front wheels 20 and 21 may be placed in the holes 18, the axle 11, of course, being also adjusted. 22 is a key-hole-shaped opening through which the knotted end of a cord or rope may be placed when not in use, the narrow part of the slot preventing accidental displacement of the cord or rope.

In Fig. V, I have shown a slightly modified form of device in which a coaster step 23 is provided, attached at its rear end to the back 9 and at its front end to the steering head by a hinge 24.

In actual practice I prefer to slot or kerf

the head longitudinally as shown to receive the hinge leaf 5 which may be fastened therein by the fastening devices 7 in an efficient manner.

Having thus described my invention, what I claim as new therein and desire to secure by Letters Patent, is:—

In a vehicle of the class described, a seat-supporting beam, a back piece attached to one end of the beam, a steering head having a kerf therein, a leaf hinge, one leaf of which is fastened with the beam, the other leaf being adjustable in the kerf, a wheel-supporting axle for the steering head, a wheel-supported axle adjustable in the back piece, and a seat on the beam.

In testimony whereof I affix my signature

MAYNOR D. BROCK.
